DIE FOR MAKING ELBOW PIPE

John Petresky, Jr., Patton, Pa., assignor to Patton Clay Manufacturing Co., Inc., Patton, Pa., a corporation of Pennsylvania

Application October 12, 1951, Serial No. 251,061

5 Claims. (Cl. 25—39)

1

My invention relates to dies and formers of the type widely used in the forming and extrusion of clay pipe, such as that used in sewer installations, and more particularly relates to dies and formers of the general type shown in U. S. Patent #2,282,282 used to manufacture pipe of plastic material, said pipe having an enlarged bell portion at one end.

The principal object of my invention is to provide a die having a lower bell portion in which the pipe bell is molded, which bell portion is opened in a novel manner to permit more efficient production of elbow pipe sections by cutting down the amount of manual labor involved in opening and closing of the bell portion.

Another primary object of my invention is to provide a novel former member adapted when engaged with the die to lock the bell portion of the die closed, and adapted when disengaged from the die to release the bell portion and permit it to swing away from the die so that the pipe may be bent around to assume an elbow shape, the purpose of the opening of the bell portion of the die being to permit the pipe to be bent nearer to the extrusion neck of the die as the pipe extrudes therefrom so that a right-angle elbow may be formed in a minimum overall length of pipe.

Broadly speaking, the mere opening of the bell portion of the die to permit sharp bending of the pipe is not novel. Hinged bell openings are shown in U. S. Patents 738,913; 2,554,011, and 2,502,247, wherein the whole bell is opened after the pipe bell has been molded. However, in these prior art patents, since the whole bell opens, it is necessary to provide latch means for holding the bell portions closed. The latch means not only unnecessarily complicates the assembly, but wastes the time of the operator who must, each time, latch and release it. In addition, it is deemed unnecessary to open the whole bell when only a segment thereof need be opened to render the die fully useful in the manufacture of elbow pipe. It is therefore an important object of my invention to provide a die wherein only a segment of the bell is opened so that the remaining portion of the bell may be formed as a strong integral part of the die, the opening segment being pivotally fixed to the die on a hinge transversely disposed with respect to the axis of the die so that upward pressure against the segment when in closed position will hold it closed, and so that release of such upward pressure will permit the segment to pivot open under the influence of gravity. The opening of only a segment of the die bell has the advantages of not only providing a stronger structure since a large portion of the bell is integral with the die, but also of providing a die which when opened projects outwardly only in one direction instead of having

2

several relatively large members projecting outwardly in several directions to take up space unnecessarily and to become a hazard to the operator. This initial opening of the segment is, moreover, assisted during the downward motion of the former member by the downward motion of that portion of the newly molded pipe bell which is in contact with the segment in its closed position.

This die lends itself to extrusion operations wherein the pipe is manually bent into elbow form, such manual bending being consistent practice in the clay pipe industry. There is, however, no reason why such a segmented bell opening can not be used in dies having mechanism for automatically bending the pipe into elbow form. In any case, it might be useful to provide bias means on the segment to force it into fully opened position as the former member retracts away from the die bell.

Other objects and advantages of my invention will become apparent during the following discussion of one practical embodiment of my invention shown in the accompanying drawings wherein:

Figure 1 is a sectional elevational of my die and former showing in dotted lines the bell segment in open position.

Fig. 2 is a bottom view of the die with the former removed.

Fig. 3 is a sectional elevation of the die extruding a right-angle elbow, the bell segment being shown in open position.

Fig. 4 is an elevation of the former member with the outer flange thereof in section.

Referring to the drawings, the device comprises an outer die 1 having an upper conical portion 1a; reducing downwardly to an extrusion neck 1b below which is a lower bell portion 1c. At the upper end of the die 1 is a flange 1d having mounting holes therethrough, this flange being useful in attaching the die to a pressurized clay reservoir (not shown). On the side of the die near the necked down portion 1b is a boss 1e for the purpose hereinafter discussed. The die has a core member 2 which may be made in separable sections as illustrated by dashed lines in Fig. 1, the core member being of rather conventional design. In addition, the die may be provided with an annular wear insert 1f at the extrusion neck 1b.

A former member 3 is provided to engage with the bell portion 1c of the die, the latter having a chamfered lower edge 1g adapted to fit into a complementary recess 3g in the former member 3, Fig. 4. A raised core portion 3a is provided in the center of the former 3 to abut against the core 2 of the die when the former is closed against the die as shown in Fig. 1. The former member 3 forms with the lower bell 1c of the die a mold which shapes the bell portion BP of the clay pipe P during the initial step in the manu-

facture of the pipe at which time the former and die are in engagement as shown in Fig. 1.

As shown in Figs. 1 and 2 a segment $1s$ of the lower bell $1c$ is openable along a line X and along lines Y . This segment $1s$ is attached to a hinge 4 , the hinge being in turn fixed to the boss $1e$ on the die. This structure permits the segment $1s$ to be pivoted inwardly to complete the annular bell $1c$, or to be pivoted outwardly as shown in Fig. 3 to open one side of the bell $1c$.

In operation, the die 1 and former 3 are closed so that the cores 2 and $3a$ abut. The clay is then pressed down through the extrusion neck $1b$ and into the pipe bell molding portion. As soon as the pipe bell BP has been formed, the former member 3 is retracted so that the chamfers $1g$ are released from the recess $3g$. The body of the pipe P begins to be extruded past the wear insert $1f$ and at this point the segment $1s$ drops downwardly and outwardly away from the pipe bell BP . The segment $1s$ can either be manually pivoted to the position shown in Fig. 3, or mechanical means may be provided to cause the segment $1s$ to automatically assume such position. The die is usually provided with a restrictor 5 just above the neck $1b$, this restrictor 5 causing less clay to pass through the extrusion neck $1b$ on the side adjacent the segment $1s$, thereby causing the pipe P to have a natural tendency to bend as it is extruded. Manual or mechanical support may be provided beneath the pipe P as it extrudes to help the pipe maintain the desired elbow angle without breakage.

When the elbow is completed and separated from the die, the segment $1s$ is again returned to closed position in which position it is tightly secured by the closing of the former member thereagainst. The die is then ready to begin the molding and extrusion of another pipe elbow.

I do not limit my invention to the exact form shown in the drawing for obviously changes may be made within the scope of the following claims.

I claim:

1. An extrusion and molding device for manufacturing elbow pipe having a pipe bell at one end, comprising a hollow die, said die having an extrusion portion terminating in an enlarged annular bell molding portion and said molding portion having a segment of its annular periphery openable and hinged to the die, a core extending through said die, and a former member adapted to engage with the molding portion to maintain the segment in closed position to complete the periphery of said molding portion and to provide a mold to form the pipe bell, said segment gravitationally hinging away from said molding portion when said former member is disengaged therefrom.

2. An extrusion and molding device for manufacturing elbow pipe having a pipe bell at one end, comprising a hollow die, said die having a vertical extrusion portion terminating below in an enlarged annular bell molding portion and said molding portion having a segment of its annular periphery openable and horizontally hinged to the die, a core extending through said extrusion portion and terminating above said molding portion; and a former member having an upwardly disposed core portion, adapted to engage upwardly with the molding portion and core to maintain the segment in closed position to complete the periphery of said molding portion and to provide a mold to form the pipe bell, said segment being released to drop by gravity

away from said molding portion when said former is lowered out of engagement therewith.

3. An extrusion and molding device for manufacturing elbow pipe having a pipe bell at one end, comprising a hollow die, said die having a vertical extrusion portion terminating below in an enlarged annular bell molding portion and said molding portion having a segment of its annular periphery openable; a core extending through said extrusion portion and terminating above said molding portion; a hinge fixed to the outside of the die and having its pivot horizontally disposed, said hinge connecting the segment and the die; and a former member having an annular recess to receive the outer periphery of the bell portion and having a core portion, said former member when engaged upwardly with the bell portion maintaining the segment in closed position to complete the periphery of said molding portion, and said core portion abutting said core to provide a mold to form the pipe bell, and said segment being released to drop by gravity away from said molding portion when said former is lowered out of engagement therewith.

4. An extrusion and molding device for manufacturing elbow pipe having a pipe bell at one end, comprising a hollow die, said die having an extrusion portion terminating in an enlarged annular bell molding portion and said molding portion having a segment of its annular periphery openable; a core extending through said extrusion portion; a hinge disposed transversely of the axis of the die and connecting the segment and the die; and a former member having an annular recess to receive the outer periphery of the molding portion and having a core portion, said former member when engaged with the molding portion maintaining the segment in closed position to complete the periphery of said molding portion and said core portion abutting said core to provide a mold to form the pipe bell.

5. An extrusion and molding device for manufacturing from material in a plastic state elbow pipe having a pipe bell at one end, comprising a hollow die, said die having an extrusion portion terminating in an enlarged annular bell molding portion and said molding portion having a segment of its annular periphery openable; a core extending through said extrusion portion; a hinge disposed transversely of the axis of the die and connecting the segment and the die; means for restricting the flow of material on one side of the extrusion portion to give the pipe a natural tendency to bend in the direction of the segment; and a former member having an annular recess to receive the outer periphery of the molding portion and having a core portion, said former member when engaged with the molding portion maintaining the segment in closed position to complete the periphery of said molding portion, and said core portion abutting said core to provide a mold to form the pipe bell, said segment being openable when said former member is disengaged from said molding portion to permit the pipe to be bent adjacent said extrusion portion as the material extrudes therefrom.
